COMBINED ASH TRAY AND PIPE REAMER

John Ward Blakely, 3704 Mound View Ave.,
Studio City, Calif.

Filed Sept. 14, 1962, Ser. No. 71,699

Term of patent 14 years

(Cl. D85—2)

Fig. 1

Fig. 3

FIGURE 1 is a perspective view of a combined ash tray and pipe reamer, showing my new design;

FIGURE 2 is a side elevational view;

FIGURE 3 is a bottom plan view;

FIGURE 4 is a top plan view; and

FIGURE 5 is a sectional view on the line 5—5 of FIGURE 4.

I claim:

The ornamental design for a combined ash tray and pipe reamer substantially as shown.
